UNITED STATES PATENT OFFICE.

RALPH C. CALLIN, OF WETMORE, COLORADO.

DESIGN FOR A DOOR KNOCKER.

Application filed May 25, 1927. Serial No. 22,155. Term of patent 3½ years.

To all whom it may concern:

Be it known that I, RALPH C. CALLIN, a citizen of the United States, residing at Wetmore, in the county of Custer, and State of Colorado, have invented a new, original, and ornamental Design for Door Knocker of which the following is a specification:

Reference being had to the accompanying drawing, forming part thereof.

I claim:

The ornamental design for a door knocker, as shown.
